UNITED STATES PATENT OFFICE.

WALTER L. PIPES, OF ELIZABETH, NEW JERSEY, ASSIGNOR TO THE GOODYEAR'S INDIA RUBBER GLOVE MFG. COMPANY, OF NAUGATUCK, CONNECTICUT, A CORPORATION OF CONNECTICUT.

LACING CLOSURE.

Application filed July 24, 1926. Serial No. 124,760.

This invention relates to a laced closure for footwear.

Buckles, multiple fasteners, and other types of closures heretofore proposed, are objectionable on one or more grounds, such as appearance, lack of adjustment, weight, cost, and difficulty of manufacture, and all around practicability for any climate and temperature. By the present invention a lacing closure for gaiters is provided which is neat in appearance, adjustable to any size of customer, of light weight, manufacturable at low cost and rapidly and easily, and it is adaptable to the requirements of climate and temperature anywhere.

With the illustrated embodiment in mind but without intention to limit more than is required by the prior art, the invention consists essentially in a combination and arrangement of a lacing with eyes and hooks such that after the initial fitting of the lacing to the customer the shoe may be completely unfastened by merely disengaging the lace from two pairs of hooks near the upper end 25 of the opening in the gaiter, and vice versa for fastening. More particularly the fastening means consists in part of eyes through which a lace is initially reeved, and in part of hooks of the ordinary kind. The second 30 and the fourth pair of fastening members, counting from the top of the gaiter, preferably are hooks of the type readily engageable or disengageable with the lacing while between them are a pair of operatively closed 35 eyes constituting a third pair of fastening means. The first or top pair of fastening members may be either eyelets extending through the fabric of the gaiter or external eyes. Preferably all of the fastening members 40 below the fourth pair are of the external eye type, with the exception of the last or bottom pair of members which, like the first, may be either eyelets or external eyes. The gaiter is initially laced as tightly as desired 45 by the wearer by reeving the lace through the eyes and around the hooks, in the ordinary manner. The ends of the lace, instead of being tied together are initially tied to the two top eyes or eyelets and thus it is

initially fitted to the requirements of the customer in as perfect a fashion as the particular last on which the gaiter has been made permits. Thereafter the ends of the lace are not freed, the gaiter being fastened or loosed by simply slipping the lace over or releasing it from the hook fastening members.

The invention will best be understood if the following description is read in connection with the accompanying drawings, in which:

Fig. 1 is a perspective view of the gaiter when closed showing both ends of the lace fastened to the upper eyes or eyelets with a finishing flap thrown back.

Fig. 2 is a top view of an external operatively closed eye member.

Fig. 3 is a longitudinal section of the same.

Fig. 4 is a top view of a hook member.

Fig. 5 is a longitudinal section of the same.

Fig. 6 is a modified form of the device shown in Fig. 1, in which the hooks are supplanted by snap fasteners one element of each of which is non-removably secured to the lace.

Fig. 7 is a top view of a modified form of eye member.

Fig. 8 is a longitudinal section of the same.

Figs. 9 and 10 are a plan view and longitudinal section, respectively, of a special form of snap fastener which may be used in lieu of the hooks.

Referring first to Fig. 1, the gaiter shown is slit from the top to a point short of the sole and is provided with a pocket of well-known form and construction indicated conventionally at 20 in the rear of the slit permitting the gaiter to be expanded for introduction and removal of the foot. Lacing means is provided consisting of a lace 21 and a number of pairs of lace engaging members along the opposed edges of the flaps formed by the slit. While any desired number of fastening members may be used, for the purpose of illustration seven pairs, numbered 21 from the top to the bottom of the gaiter, are shown in Fig. 1. Fastening members 2 and 4 are preferably hooks with which the lace

is readily engageable or disengageable at will. Members 3 located between members 2 and 4, and members 5 and 6, are external operatively closed eyes through which the 5 lace is reeved. The members 1 and 7 may be external eye members or eyelet members extending through the fabric of the gaiter, but are preferably of the latter type. The gaiter is initially laced as tightly as desired 10 by the wearer, the lace being threaded through eyelets 7 and its ends reeved through the members 6 and 5, hooked over the members 4, reeved through the members 3, hooked over the members 2 and threaded through and tied to the members 1, the lace being crossed 15 between each pair of fastening members. Since the ends of the lace are initially secured respectively to the fastening members 1, the operation of knotting together the ends of the 20 lace at the top of the gaiter is eliminated. It will be readily apparent that when the lacing is disengaged from the hook members comprising the second and fourth pairs of fastening means, the slit or opening of the gaiter 25 may be separated completely so as to permit the gaiter to be readily removed, the slack supplied from the portions of the lace released from the hooks being sufficient to furnish and allow enough separation of the 30 lower pairs of eyes 5 and 6. The gaiter may be fastened by first drawing tight on the laces through the mere engaging of the lacing with the hook members 2 and 4.

In Fig. 6 a modified form of fastening 35 means is shown, snap members 10 being substituted for the hook members 2 and 4. The eye members 8 are similar to the eye members shown in Fig. 1 except that they conform in shape to the snap members. The 40 snap members each consist of two parts, a fixed part 9 secured to the body of the gaiter, and a free part 10 which is adapted to fit over and fasten to the fixed part in a well-known manner. The upper part 10 of each 45 snap is provided upon its periphery with a loop 11 by which it is easily threaded on the lace. The free part of each snap member is engageable with the fixed part of the snap oppositely located on the other flap. Since 50 the lace is threaded through the upper parts of the snap members, lacing is accomplished when the snap members are fastened. With this modified form of fastener the gaiter may be closed substantially as above described.

55 The fastening means disclosed above provides a quick and easy way of fastening and unloosing overshoes or gaiters and obviates the necessity of tying and untying the ends of the lace whenever the gaiter is put on or removed.

The distance between the pairs of fastening members 2, 3, 4, and 5, particularly, in the gaiter type overshoe for which the invention is primarily intended is ordinarily so great 65 as to be likely to produce wrinkles at the

abutting margins of the cup opening thereof. To prevent such wrinkles and thereby enhance the appearance of the shoe it is preferred to provide some form of stiffening means such as steel stays or wire, the wire 70 being illustrated in the drawing as indicated at 30.

It is preferred also to provide for gaping or spreading apart of the upper end of the opening of the overshoe by providing positive means for closing the same, such for instance, as the flap 31 which is preferably permanently secured by stitching as indicated at 32 near the top of the shoe, a snap fastener, as indicated at 33 and 34 respectively, being provided for securing the other end of the strip to the other side of the opening. And preferably also, strip 31 is located 80 so as to conceal the knotted or otherwise permanently secured end of the lace. 85

Having thus described my invention, what I claim and desire to secure by Letters Patent is:

1. A lacing closure for footwear having an opening for facilitating introduction and removal of the foot, comprising a lace having its ends permanently secured to the opposite sides respectively of the opening adjacent the top of the shoe, a series of members for holding the lace in criss-cross relation on the outside of the shoe, said members including a pair of eyes permanently secured to the opposite sides of the opening and through which the lace is passed, pairs of members above and below said pairs of eyes by which the lace 90 may be separably secured to opposite sides of the opening and means for stiffening the edges of the opening to prevent wrinkles. 95

2. A lacing closure for footwear having an opening for facilitating introduction and removal of the foot, comprising a lace permanently secured to the sides of the opening adjacent the top of the shoe, a series of members for holding the lace in criss-cross relation on the outside of the shoe, said members including a pair of eyes permanently secured to the opposite sides of the opening and through which the lace is passed, pairs of members above and below said pairs of eyes by which the lace may be separably secured to opposite sides of the opening, means for 100 stiffening the edges of the opening to prevent wrinkles, and means independent of the lace 105 adapted to span the opening and positively secured on opposite sides thereof. 110

3. A lacing closure for footwear having an opening for facilitating introduction and removal of the foot, comprising a lace permanently secured to the sides of the opening adjacent the top of the shoe, a series of members for holding the lace in criss-cross relation on the outside of the shoe, said members including a pair of eyes permanently secured to the opposite sides of the opening and through which the lace is passed, pairs of 115 members 120

members above and below said pairs of eyes by which the lace may be separably secured to opposite sides of the opening, means for stiffening the edges of the opening to prevent wrinkles, and means independent of the lace adapted to span the opening and positively secured on opposite sides thereof, said

last named means located to conceal the upper secured ends of the lace.

Signed at New York, county of New York, 10 State of New York, this 13th day of July, 1926.

WALTER L. PIPES.
